PENCIL AND ERASER

Arthur W. Forsyth, Maplewood, Mo., assignor to
 Wallace Pencil Company, St. Louis, Mo., a corporation of Missouri

Application March 26, 1938, Serial No. 198,199

4 Claims. (Cl. 120—38)

My invention relates to the mounting of erasers on the ends of pencils and has for its principal objects to provide a larger eraser, to improve the appearance of the eraser end of the pencil, to mount the eraser more firmly in place and to accomplish other objects and advantages that will be hereinafter pointed out.

The invention consists principally in fixing on the end of a pencil a metal ferrule having a portion of reduced diameter, which extends into a recess in a rubber eraser, the tip of said ferrule having rebent hooks or barbs that securely fasten the eraser and ferrule together.

In the accompanying drawing,

Fig. 1 is an elevation of a pencil and eraser construction embodying my invention; and

Fig. 2 shows the eraser in longitudinal section, with a portion of the ferrule cut away to show the ferrule partly in longitudinal section.

The drawing illustrates a portion of a pencil A of the well-known hexagonal type. Mounted on the end of said pencil is a metal ferrule B. The metal ferrule B includes a portion 1 of substantially the same outside diameter as the pencil, said portion being given any desired ornamental finish as shown by the ribs 2 and knurls 3 of the drawing.

The ferrule B has an elongated cylindrical portion 4 of somewhat reduced diameter. A portion 5 of the wooden barrel of the pencil of reduced diameter to fit the reduced portion 4 of the ferrule extends a considerable distance into said reduced portion 4; and the ferrule is secured to the wooden barrel by stamping or punching portions 6 of the ferrule into the barrel.

At its outer end the ferrule B is provided with barbs or prongs 7 that are rebent into proximity with the outer surface of the ferrule. A rubber eraser 8 having an axial recess 9 whose depths is equal to the distance from the outermost rib to the end of the ferrule is forced over the cylindrical reduced portion 4 of the ferrule, into abutment with said outermost rib 2. The recess 9 has an inside diameter such as to fit snugly on the reduced portion 4 of the ferrule and the prongs or barbs 7 of the ferrule will dig into the eraser material to prevent withdrawal thereof.

The above described construction makes possible the use of an eraser of any desired size, the amount of eraser material available for erasing being obviously much greater than in the case of an ordinary eraser mounted inside a metal ferrule. 5 The eraser is more firmly supported than ordinary erasers, by reason of the depth to which the ferrule extends into the eraser and the wooden barrel of the pencil extends into the ferrule. The unsightly punches usually required to secure the 10 ferrule to the pencil and to secure the eraser inside the ferrule are eliminated, the only punch marks being concealed by the eraser. The eraser can obviously be given a square or other desired shape without sacrificing its stability on the 15 pencil.

What I claim is:

1. A pencil having a hollow ferrule mounted thereon and an eraser mounted on said hollow ferrule, said ferrule having rebent prongs holding 20 the eraser in place.

2. A pencil and eraser construction comprising a pencil, a hollow metal ferrule mounted on the end thereof having a projecting cylindrical portion and an eraser having an axial recess receiving said projecting portion of said ferrule, said ferrule having rebent prongs at its outer end preventing removal of the eraser. 25

3. A pencil and eraser construction comprising a pencil, a hollow metal ferrule mounted on the end thereof having a projecting cylindrical portion of reduced diameter and an eraser having an axial recess receiving said projecting portion of said ferrule, said ferrule having rebent prongs at its outer end preventing removal of the eraser. 30

4. A pencil and eraser construction comprising a pencil, a hollow metal ferrule mounted on the end thereof having a circumferential rib and having a cylindrical portion of reduced diameter projecting beyond said rib and an eraser having an axial recess receiving said projecting portion of said ferrule, the end of said eraser being seated against said rib, said ferrule having rebent prongs at its outer end preventing removal of the eraser. 40

ARTHUR W. FORSYTH.
